UNITED STATES PATENT OFFICE.

SIGMUND BOWER, OF BROOKLYN, NEW YORK.

REENFORCED CLOTHESPIN AND THE METHOD OF MAKING SAME.

Application filed March 7, 1927, Serial No. 173,825. Renewed June 11, 1928.

The present invention relates to a clothes pin having a reenforcing attachment to prevent splitting and it also relates to a new and novel method of making such reenforced clothes pin. The common type of clothes pin made of wood with a slot sawn therein to provide prongs for straddling the clothes line and a portion of the clothes, is weak in construction, due to the tendency of the pin 5 to split in the direction of the saw cut when the prongs are spread in the process of applying the pine to the line and clothes, the split taking place usually in the direction of the length of the pin and therefore in 10 the direction of the grain of the wood. In my U. S. Patent No. 1,592,334, dated July 18th, 1926, I showed and described a reenforcement adapted to be made of wire and afterwards applied to the clothes pin. In 15 20 25 30 35 40 45 50

In the present invention the reenforcing member is formed or constructed upon the pin, using the latter as the form or mandrel in the construction of the reenforcing member. The object of the invention in so far as 20 25 30 35 40 45 50

the product itself is concerned is to provide a tight fitting and firm holding reenforcing member encircling the clothes pin at its weakest point, the ends of the reenforcing member projecting into the slot in the clothes pin and frictionally engaging with the walls of the slot to resist the expansion of the reenforcing member and also securing it firmly in place upon the clothes pin. Another object is to provide a reenforcement member which will fit tightly upon the clothes pin and thereby prevent the latter from splitting, and which will permit the application of a tight fitting reenforcement member notwithstanding the variations in 40 45 50

the proportions of the clothes pins which occur in the ordinary methods of manufacture. Although clothes pins are usually turned in a lathe and are intended to be of uniform size, nevertheless in actual production there is a wide variation, both in the diameter of the pins and in the length of of the saw cut or slot; but notwithstanding these variations the present reenforcement member is made to fit tightly upon the clothes pin so that it properly serves its purpose of reenforcing the clothes pin and retaining its position thereon throughout the life of the article.

In so far as the method of making the product is concerned, the object is to provide a simple and efficient method of rapidly

applying the reenforcement members to the clothes pins so that each reenforcement member accurately and tightly fits its respective clothes pin notwithstanding the 60 variations in the sizes of the pins as commercially manufactured. The broad feature of this method consists in inserting one end of a strip of wire, of which the reenforcing member is to be made, into the slot of the 65 clothes pin, near its inner end; then bending the wire tightly around the outside or periphery of the clothes pin to encircle it circumferentially; and afterwards forcing the second or free end of the wire into the slot 70 of the clothes pin to maintain the necessary tension of the reenforcing ring upon the pin. Other features and advantages will be set forth in the following detailed description 75 of my invention.

In the drawing forming part of this application,

Figure 1 is a side elevation of the completed reenforced clothes pin embodying my invention, and showing the same on a scale 80 larger than the usual type of clothes pin for the purpose of more clearly illustrating the details,

Figure 2 is a sectional view taken on the line 2—2 of Figure 1,

Figure 3 is a cross sectional view taken on the line 3—3 of Figure 1,

Figure 4 is a sectional view illustrating the first step in the method of applying the reenforcing member and it is taken in the 90 same position as Figure 3,

Figure 5 is a similar sectional view showing the reenforcing member after it has been wound one and one-half times around the clothes pin, and

Figure 6 is a similar view showing the completion of the reenforcing member by the forcing in of the second or free end of the wire into the slot of the clothes pin.

I will first describe the product as it is 100 illustrated in Figures 1 to 3, and I will then describe the method by which the product is produced. Herein I have shown a clothes pin 1 of the ordinary type, which is generally made by turning a piece of wood in a suitable lathe to form a rounded body portion 2 having the flange or head 3 at one end. The opposite end of the clothes pin is formed into resilient, substantially parallel prongs or tines 4 by forming a slot 5 longitudinally of the pin, generally by means of a saw cut or cuts; and usually the lower

or end opening of the cut is tapered or enlarged as shown at 6 to provide wedge shaped inner surfaces on the prongs of the pin to facilitate the initial application of the pin to the clothes line and fabric. The reinforcing member is preferably made of wire which encircles the clothes pin adjacent the inner end of the slot 5 where the clothes pin is most likely to split when the prongs 10 are sprung apart. As shown in the drawing, one end 7 of the wire 8 extends inwardly within the slot 5 of the clothes pin, in a direction somewhat radially of the periphery of the clothes pin, so that this member 15 frictionally contacts with the wall of the slot 5 at the point 9 and also with one corner 10 of the wall of the slot; and preferably at this point of contact the wire is slightly pressed into the wood to prevent shifting of 20 the reenforcing member lengthwise of the clothes pin. From the inturned portion 7 the wire member 8 extends around the periphery of the clothes pin in the form of a circular band 11 which encircles the clothes 25 pin approximately one and one-half turns, the half turn 12 lying close to and parallel with the full turn 11. The second or last end of this wire is drawn or forced into the slot 5 of the clothes pin in order to form a 30 loop 13 the opposite arms 14, 15 of which exert opposing pressures against the opposite side walls of the slot 5 of the clothes pin. This loop is wedged between the walls 35 of the slot 5 and lies adjacent to the end 7 and its resists any tendency of the wire to expand. The two ends of the wire being 40 thus locked within the slot of the clothes pin, the portions which encircle the pin are held tightly around its circumference and serves to prevent the clothes pin from splitting on 45 a line extending from the slot 5 which is the weak portion or the portion which is subject to the splitting action when the clothes pin is applied to a line. If the two prongs 4 of the pin are forced over a clothes 50 line and fabric thereon with sufficient pressure to tighten the pin upon the line, the strength of the clothes pin, or its resistance to splitting is substantially increased by the reinforcement described, so that the pin 55 may be forced into tighter engagement with the line and fabric than the ordinary clothes pin, and without causing the pin to split.

The method carried out in the formation of the present device is illustrated in Figures 4 to 6 inclusive and is as follows: First, the wire 8 is provided with a bent portion 7 approximately at right angles to the main portion 8 of this wire, and the latter may 60 be of any desired length. For instance, it may be a long strand of wire feeding from a spool or supply, and the free end is bent at an angle as shown in Figure 4. The clothes pin is then placed in such relation 65 to this bent portion 7 that the latter ex-

tends into the slot 5 of the clothes pin adjacent the top shoulder or end wall 16 of the slot. The next step is to bend the portion 8 of this wire around the periphery of the clothes pin adjacent the inner end of the slot 5 as shown in Figure 5, until the wire extends approximately one and one-half turns around the clothes pin with the end 17 extending across one open side of the slot 5. If the wire is a long or continuous piece it may now be cut off at approximately the point shown in Figure 5, leaving a free end 17 adjacent the clothes pin. This free end is now forced into the slot 5 of the clothes pin by any suitable tool so that a 75 loop 13 is formed in this end of the wire, the loop extending into the slot 5 as previously described in connection with the product. It is preferable to hold the wire closely to the periphery of the clothes pin as it is 80 being wound into the position shown in Figure 5 and until the hooked end 13 has been formed in the slot 5 of the pin, after which any pressure outside of the wire may be released because the wire is now so held 85 upon the pin that it cannot expand. In the operation of forcing the end 17 into the slot of the pin the wire bends at the point 18 and slightly forces into the edge 19 of the clothes pin, forming a slight indentation, 90 and this, together with the indentation made by the first portion of the wire at 20, serve to prevent the reenforcing member as a 95 whole from sliding lengthwise of the pin, in addition to such gripping action as may be 100 caused by the tension of the reenforcing member against the clothes pin.

In carrying out the method the clothes pin itself may be gripped by suitable jaws, (not shown) and it may be revolved in such manner that the clothes pin itself acts as a mandrel on which the reenforcing member is formed. This is a decided advantage and is one of the main features of the method because each reenforcing member 105 will conform accurately to the dimension of the clothes pin to which it is attached, so that if the clothes pins vary in diameter, as they usually do in the ordinary course of manufacture, the individual clothes pin determines the dimension of its respective re-enforcing member so that each reenforcing member may be made to grip or hold its respective pin sufficiently tight to accomplish its purpose and also to prevent it from 110 being dislodged.

While I have described the reenforcing member as made of wire, and while I have shown in the drawing a round wire used for the purpose, it is to be understood that any 115 material susceptible of the formation shown may be used without departing from the spirit and scope of my invention.

Having described my invention, what I claim is:

1. A method of reenforcing clothes pins which consists of associating with a clothes pin a member such as a wire, having one end bent at an angle to the main portion thereof so that said bent end extends laterally into the slot of the clothes pin, thence bending the main portion of said wire circumferentially around the clothes pin, employing the clothes pin as a mandrel in said operation, and then forcing the other end of said wire into the slot in the clothes pin in such manner as to form a loop in said end, the legs of which press against opposite walls of said slot in the clothes pin.
  2. In an article of the class described the combination of a slotted clothes pin and a reenforcing member therefor, comprising a ring extending around the clothes pin adjacent the inner end of the slot thereof, said ring having its free ends extending inwardly into the slot of said clothes pin, one of said ends being bent to form a loop within the slot of the clothes pin.
  3. In an article of the class described the combination of a slotted clothes pin and a reenforcing member therefor, comprising a ring extending substantially one and one-half turns around the clothes pin adjacent the inner end of the slot thereof, said reenforcing member having its free ends extending inwardly into the slot of said
- clothes pin from opposite sides, at least one of said free ends being bent to form a loop within the slot of the clothes pin.
4. In an article of the class described the combination of a slotted clothes pin and a reenforcing member therefor, comprising a ring extending substantially one and one-half turns around the clothes pin adjacent the inner end of the slot thereof, said reenforcing member having its free ends extending inwardly into the slot of the clothes pin from opposite sides thereof, said ends projecting in substantially parallel relation transversely of said slot and one of said free ends being bent to form a loop within the slot of the clothes pin.
  5. In an article of the class described the combination of a slotted clothes pin and a reenforcing member therefor, comprising a ring extending around the clothes pin adjacent the inner end of the slot thereof, said reenforcing member having its free ends extending inwardly into the slot of said clothes pin, at least one of said ends having a loop formed therein, within said slot, the legs of said loop being under tension and pressing against the opposite walls of the slot of the clothes pin.

Signed at the city, county and State of New York, the first day of March, 1927.

SIGMUND BOWER.
